[57] **CLAIM**

The ornamental design for a frame for mirrors, pictures, and combinations thereof, as shown and described.

DESCRIPTION

FIG. 1 is a perspective view of a frame for mirrors, pictures, and combinations thereof showing my design;

FIG. 2 is a front elevational view thereof;

FIG. 3 is a back elevational view thereof;

FIG. 4 is a top plan view thereof;

FIG. 5 is a bottom plan view thereof;

FIG. 6 is a side elevational view thereof;

FIG. 7 is a side elevational view thereof opposite that shown in FIG. 6;

FIG. 8 is a perspective view of an alternate embodiment of a frame for mirrors, pictures, and combinations thereof showing my design;

FIG. 9 is a front elevational view thereof;

FIG. 10 is a back elevational view thereof;

FIG. 11 is a top plan view thereof;

FIG. 12 is a bottom plan view thereof; and,

FIG. 13 is a side elevational view thereof, the opposite side being a mirror image thereof.
